UNITED STATES PATENT OFFICE

153,859

DESIGN FOR A COSMETIC HOLDER

Walton B. Crane, Beverly Hills, Calif., assignor
to Max Factor & Co., Hollywood, Calif., a corporation of Delaware

Application May 3, 1948, Serial No. 146,141

Term of patent 14 years

(Cl. D86—10)

To all whom it may concern:

Be it known that I, Walton B. Crane, a citizen of the United States of America, residing at Beverly Hills, county of Los Angeles, State of California, have invented a new, original, and ornamental Design for a Cosmetic Holder, of which the following is a specification, reference being had to the accompanying drawings, forming a part thereof.

Figure 1 is a front elevational view of a cosmetic holder showing my new design;

Figure 4 is an exploded view showing the cap
in spaced relation above the base.

I claim:

The ornamental design for a cosmetic holder,
substantially as shown.

WALTON B. CRANE.
